UNITED STATES PATENT OFFICE

2,509,550

RESERVOIR HANDLE APPLICATOR WITH
HAND CONTROLLED FEED VALVEEleanor L. Woods, Chicago, Ill., now by judicial
change of name Eleanor A. Peterson

Application December 11, 1945, Serial No. 634,361

2 Claims. (Cl. 15—138)

1
This invention relates to cleaning devices and more particularly to a nail cleaning composition applying applicator.

A main object of the invention is to provide a novel and improved nail cleaning composition applying device which is extremely simple in construction, efficient in operation and easy to use.

A further object of the invention is to provide an improved nail cleaning composition applying device which may be easily held by the manicurist during the nail-cleaning operation without the manicurist coming in contact with the nail cleaning fluid, whereby the manicurist may wear nail polish while working.

Further objects and advantages of the invention will become apparent from the following description and claims, and from the accompanying drawing, wherein:

Figure 1 is a side elevational view, partly in section, of a nail cleaning composition applying device according to this invention.

Figure 2 is a detail vertical longitudinal cross-sectional view of the fluid-dispensing end portion of the device of Figure 1.

Figure 3 is a bottom view of the fluid-dispensing end portion of the device of Figure 1.

Figure 4 is a vertical cross-sectional view taken on line 4—4 of Figure 2.

Figure 5 is a fragmentary sectional view showing a portion of the clamp.

Referring to the drawings, 11 designates the barrel portion of the nail cleaning composition applying device forming a handle, said barrel portion being hollow and having a removable end cap 12 for opening the barrel to fill it with nail cleaning fluid. Barrel 11 is threadedly secured to a relatively short forward section 13 which is formed with an internal axial tubular neck 14. Tubular neck portion 14 contains a longitudinal rod member 15 forming a valve stem which is slidably mounted in the front wall of forward section 13, said rod having a button 16 at its front end and a conical valve element 17 at its rear end adapted to cooperate with a valve seat 17' formed in the rear wall 39 of forward section 13 to control the admission of cleaning fluid into tubular portion 14. A coil spring 18 is positioned on rod 15 between head 16 and the front wall of forward section 13 to bias valve element 17 to a seated position. The lower forward portion of neck 14 is formed with a plurality of openings 19 adapted to allow the nail cleaning fluid to flow outwardly therefrom. Adjacent openings 19, the outer wall of forward section

13 is formed with an enlarged opening 20 approximately the size and shape of a finger nail in which a cotton pad 21 is adapted to be positioned. Cotton or absorbent pad 21 is removably secured to forward section 13 by a pair of clamping fingers 22, 22, said clamping fingers being upwardly and rearwardly curved and being loosely supported on a transverse pin element 23. The upper ends of fingers 22, 22 project through a slot 24 in the top wall of forward section 13 and are formed with top tab portions 25, 25. A coil spring 26 is positioned on pin element 23 between fingers 22, 22 and biases said fingers apart. The top wall of forward section 13 is formed with depending pivot lugs 27, 27 below pin element 23, spring 26 cooperating with pivot lugs 27, 27 to provide a co-acting means for causing normal clamping action for fingers 22, 22 with respect to the cotton pad 21 positioned between the lower portions of fingers 22, 22 in the opening 20.

In operation, the head 16 of valve rod 15 is pushed rearwardly allowing cleaning fluid to flow past valve element 17 into tube 14 and through openings 19 on to the cotton pad 21. When the cotton pad is saturated with fluid, head 16 is released and the device is applied to the finger nail to be cleaned with a rubbing or wiping action. After the finger nail is cleaned, the cotton pad may be removed by pressing tabs 25, 25 together, thus releasing the clamping members 22, 22 from engagement with the cotton pad. A new cotton pad is then inserted between the clamping members 22, 22 and the device is ready for the next cleaning operation.

As shown in Figure 2, a recess 28 is formed in the forward portion of section 13 to receive head 16 when the fluid valve is to be opened. By pressing the forward end of the device with the tip of a finger the head 16 may be pushed inwardly until it is flush with the front end portion of section 13, thus opening the valve.

While a specific embodiment of a manicure removing device has been disclosed in the foregoing description, it will be understood that various modifications within the spirit of the invention may occur to those skilled in the art. Therefore it is intended that no limitations be placed on the invention other than as defined by the scope of the appended claims.

What is claimed is:

1. In a nail cleaning composition applying device, a hollow, tubular handle adapted to receive and hold a supply of liquid nail cleaning composition, a forward hollow section secured to the

forward end of said handle and in communication with the latter, there being an opening in the wall of said section adjacent the front end thereof, a tubular neck provided with a plurality of spaced openings in the lower portion of its wall adjacent the forward end mounted within the interior of said section, the rear wall of said section being provided with a valve seat, a longitudinal stem slidably mounted in the front wall of said section and extending through said neck, a valve element on the rear end of said stem and adapted to cooperate with said valve seat, resilient means operatively connected to said stem for biasing the valve elements of the latter into seating relation with respect to said valve seat, a pair of clamping fingers arranged within said forward section adjacent the opening in the latter and mounted for movement toward and away from each other for receiving therebetween an absorbent pad positioned in the latter-named opening, and coacting means on said clamping fingers and said forward section for causing normal clamping action of the fingers with respect to said pad when the latter is positioned in the opening of the forward section.

2. In a nail cleaning composition applying device, a hollow, tubular handle adapted to receive and hold a supply of nail cleaning composition, a forward hollow section having a slot in the top portion thereof secured to the forward end of said handle and in communication with the latter, there being an opening in the lower portion of the wall of said section adjacent its front end thereof, a tubular neck provided with a plurality of spaced openings in the lower portion of its wall adjacent the forward end mounted within the interior of said section, the rear wall of said section being provided with a valve seat,

a longitudinal stem slidably mounted in the front wall of said section and extending through said neck, a valve element on the rear end of said stem and adapted to cooperate with said valve seat, resilient means operatively connected to said stem for biasing the valve element of the latter into seating relation with respect to said valve seat, a pair of clamping fingers arranged within said forward section adjacent the opening in the latter and mounted for movement toward and away from each other for receiving therebetween an absorbent pad positioned in the latter-named opening, said clamping fingers being upwardly and rearwardly curved and having their upper ends projecting through the slot in said forward section, hand-gripping means on the ends of the fingers for actuating the latter, and co-acting means on said clamping fingers and said forward section for causing normal clamping action of the fingers with respect to said pad when the latter is positioned in the opening of the forward section.
